UNITED STATES PATENT OFFICE.

HUGH C. KELLEY, OF SONORA, TEXAS.

SHAVE-REGISTERING DEVICE.

No. 866,142.

Specification of Letters Patent.

Patented Sept. 17, 1907.

Application filed December 21, 1906. Serial No. 348,946.

To all whom it may concern:

Be it known that I, HUGH C. KELLEY, a citizen of the United States, residing at Sonora, in the county of Sutton and State of Texas, have invented a new and useful 5 Shave-Registering Device, of which the following is a specification.

This invention relates to shave registering devices of that type which depend for their operation upon the relative changes in position of the back and other parts 10 of a barber's chair during the adjustment of the chair to and from an inclined position for shaving the occupant.

The invention has for one of its objects to provide a device of this character which is of simple and durable 15 construction, comparatively inexpensive and easy to manufacture and thoroughly reliable and efficient in use.

A further object of the invention is the provision of a registering device mounted in the back of the chair 20 and operated by a resilient rod attached at one end to one of the arms of the chair and movable at its opposite end in a slot provided in the back to move into and out of operative relation with the said device, thereby indicating the movements of the parts of the chair every 25 time a person is shaved.

With these objects in view, and others, as will appear as the nature of the invention is better understood, the invention comprises the various novel features of construction and arrangement of parts, which will be more 30 fully described hereinafter and set forth with particularity in the claims appended hereto.

In the accompanying drawing, which illustrates one of the embodiments of the invention, Figure 1 is a perspective view of a portion of a barber's chair showing 35 the registering apparatus applied thereto. Fig. 2 is a fragmentary rear view of the back of the chair partly broken away to show details of construction. Fig. 3 is a similar view showing a modified form of device. Fig. 4 is a detail view of the resilient actuating rod shown 40 in Figs. 1 and 2. Fig. 5 is a side view of a barber's chair showing a modified form of registering device applied thereto. Fig. 6 is a detail view of a portion of the registering device.

Corresponding parts in the several figures are indicated throughout by similar characters of reference. 45

Referring to the drawing, 1 designates the back of a chair suitably hinged to the upper ends of the legs 2 so as to freely swing from an upright to an inclined position, or vice versa, and 3 are the arms of the chair. 50 These parts may be of any approved construction, since the invention is not necessarily limited to this particular form of chair.

Arranged on the back 1, and preferably embedded therein, is the registering device 5 having a dial 6 and 55 a hand 7, both of which are exposed at the rear of the

back 1. A suitable step by step mechanism is employed for actuating the hand and the same preferably comprises a toothed wheel 8, an active pawl 9 and a back acting pawl 10. These parts are supported on the frame 11, which is secured to the side member 12 of the 60 back 1. The pawl 9 is formed on the inner end of the push rod 13 which is longitudinally movable in the opening 14 of the member 12. The member 12 is provided with a vertically extending slot 15 which is open at its front and the end of the push rod opposite from 65 the pawl extends normally a suitable distance into the slot. Bearing on the push rod is a leaf spring 16 extending lengthwise of the slot and anchored therein, and having a normal deflection away from the wall of the slot to which one end is attached, as shown in Fig. 2. 70 By this means, the leaf spring 16 is adapted to be straightened out and pressed against the wall of the slot and thereby impart movement to the push rod 13. The push rod is provided with a helical compression spring 17 which returns it to normal position. 75

The actuator for the leaf spring 16 comprises a resilient rod 18 of suitable stiffness which at one end is provided with a ball 19 confined in the slot 15 so as to have a wiping engagement along the leaf spring. The end of the actuator rod opposite from the ball is secured to 80 the arm 3 adjacent the member 12. At a suitable point intermediate its ends, the rod is turned into a coil 20 so as to increase its flexibility. The arrangement of these parts is such that when the back 1 of the chair is in an upright position, the ball 19 is at the upper end of the 85 slot 15. As the back of the chair is inclined rearwardly to the usual shaving position, the ball 19 moves lengthwise of the slot and engages with the spring 16, so that the push rod is actuated and, through the same, the indicating device, so that hand is advanced another point. After the person in the chair has been shaved, the back is moved upwardly to the position shown in Fig. 1 for the purpose of permitting the barber to dress the hair. The ball 19 is returned to its normal position so as to permit the spring 16 and pawl 9 to move 90 into position for further actuation when the back is again inclined. It will thus be seen that the necessary movements of the back of the chair during the shaving of customers are accurately registered for the convenience of the proprietor. 95

In the modification shown in Fig. 3, the actuating rod 21 is provided with a laterally extending arm 22 that projects through the slot 23 open at both ends in the sides of the member 24 of the back of the chair. The inner end of this arm engages with a vertically extending combined push rod and pawl 25 of the indicating mechanism, which mechanism is substantially the same as that described in connection with the other figures. In this construction, the arm 22 moves from one end of the slot to the other as the back 1 is swung 100 110

from an upright to an inclined position, or vice versa, so as to actuate the push rod 25 and cause the registering device to indicate.

Referring to Figs. 5 and 6, 26 represents a barber's chair having a seat 27, back 28, and leg rest 29 of ordinary construction mounted so that the leg rest is swung upwardly as the back 28 is inclined rearwardly, as will be readily understood. The indicating device, designated generally by 30, is embedded in the back 28 and is of substantially the same construction as that described in connection with the other figures. The active pawl 31 of the indicating mechanism is connected with the lever 32 which, in turn, is connected by means of the cord or other flexible element 15 33 to the leg rest. This cord extends downwardly from the lever 32 in the back 28 and over a pulley 34 on the seat 27, thence under the seat to the leg rest. Included in this flexible element is a helical extension spring 35. By this construction, the active pawl 34 is operated 20 each time the back 28 and leg rest 29 are moved for the purpose of throwing the occupant of the chair into the desired shaving position, draft being produced on the cord 33 as the position of the back and leg rest is changed. After the person is shaved, the movable

parts of the chair are returned to their normal position 25 and the pawl 31 is retracted and the spring 35 contracts so that the cord is maintained taut.

I have described the principle of operation of the invention, together with the apparatus which I now consider to be the best embodiment thereof, but I desire 30 to have it understood that the device shown is merely illustrative, and that various changes may be made, when desired, as are within the scope of the claims.

What is claimed is:—

The combination of a barber's chair comprising a movable back provided with a slot, and arms movable with respect to the back, with a registering device mounted on the back, a push rod for actuating the said device and extending into the slot, a leaf spring in the slot engaging the push rod, a resilient member connected with one of 40 the arms and extending into the slot, and an enlargement on the member arranged to have a wiping engagement with the leaf spring.

In testimony that I claim the foregoing as my own, I have hereto affixed my signature in the presence of two 45 witnesses.

HUGH C. KELLEY.
